UNITED STATES PATENT OFFICE.

WILLIAM H. BAKER, OF CENTRAL FALLS, RHODE ISLAND, AND FREDERIC E. KIP, OF MONTCLAIR, NEW JERSEY.

LOOM.

SPECIFICATION forming part of Letters Patent No. 633,944, dated September 26, 1899.

Application filed March 4, 1899. Serial No. 707,772. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Looms, of which the following is a specification.

This invention relates to that class of devices employed for automatically supplying filling or weft to the shuttle of a loom; and it has for its object partly to employ electricity for controlling and determining the supply of filling and partly to provide simple and efficient mechanical means for carrying out the invention, all as will be more particularly hereinafter described.

In the accompanying drawings, which serve to illustrate an embodiment of the invention, Figure 1 is a front view of an ordinary loom provided with the improved weft-supplying mechanism, the latter being represented in this view on a small scale. Figs. 2, 3, 3^a, 4, and 5 are views of the weft-supplying mechanism on a larger scale, Fig. 2 being a front view as seen from the right in Fig. 3; Fig. 3, a vertical section substantially at line $\alpha\alpha^3$ in Fig. 2; Fig. 3^a, a fragmentary sectional view at line $\alpha^3\alpha^3$ in Fig. 2 similar to Fig. 3, but showing the bobbin-carrier in a different position; Fig. 4, a horizontal section taken through the inclosing casing and carrier above rack 11, seen in Fig. 3; and Fig. 5, a fragmentary face view of the carrier, showing one of the fingers thereon. Fig. 6 is a side view of the shuttle-box, and Figs. 7 and 8 are respectively a plan and a side view of the shuttle detached.

These views are on a larger scale than the preceding figures. Fig. 9 is a sectional plan view, on a large scale, of parts of the shuttle-box, shuttle, bobbin-box, and bobbin, illustrating the electrical connections; and Fig. 10 is an end view of the bobbin-box and bobbin. Figs. 11 and 12 are views of the bobbin-box and bobbin, illustrating modified forms of the contact devices on the bobbin.

Fig. 1 is merely an illustrative view designed to show the position of the weft-supplying device on the loom.

F is the loom-frame; L, the lay; B, the shuttle-box thereon; P, the picker-sticks; S, the

shuttle, and W in Fig. 1 the weft-supplying mechanism as a whole. Respecting this latter mechanism, which is best seen in the detail views, 1 is a strong bracket mounted on the loom-frame, and 2 is an upright magazine which holds the bobbins, each inclosed in a bobbin-box 3. The bobbin-boxes rest one on another or superposed in the magazine, and they are taken from the bottom of the magazine one by one by a rocking carrier and transferred to the shuttle S, the incoming bobbin-box displacing that already in the shuttle.

Mounted to rock in bearings 4 4 in Figs. 2 and 4 in the bracket 1 is a shaft 5, on which is fixed the carrier 6. This carrier is in the form of a frame of quadrant shape, as seen in Fig. 3, and carrying one section 7 of the semicylindrical inclosing casing, the other section 7^a thereof being fixed in position and connected with the magazine 2. This magazine may be composed, as here shown, of two like upright end pieces or keepers, in which the respective ends of the bobbin-boxes 3 are guided in their descent, as by gravity, to the point where the rocking carrier-frame 6 takes them.

It may be well to explain here that the bobbin-box 3 is of elongated form, of stiff thin material, preferably sheet-steel, and of such size and proportions as to fit into the hollow of the shuttle S. Each box 3 has formed in it a mortise or socket 3^a, Fig. 8, near each end thereof, to receive flat carrying pins or fingers 6^a on the frame 6. As the lower bobbin-box descends from the magazine (see Fig. 3) it engages the fingers 6^a and is ready to be transferred to the shuttle.

The electrical devices will now be described.

On the lay L is mounted a stout bracket 8, Figs. 3 and 3^a, which supports an electromagnet M, and an elbow-shaped armature-lever 9, carrying the armature m. The upper arm of the lever 9 has a toe 9^a, which when the magnet M is excited and attracts its armature is projected upward through an aperture in the horizontal arm of the bracket 8. The bracket 8 and magnet M move to and fro, the lay of course being mounted thereon. Mounted to slide in a guideway in the bracket 1 is a rack 10, which plays directly over the bracket 8, and gearing with this rack is a circular

rack 11, fixed to the rocking carrier 6 and concentric with the shaft 5. Now if the electromagnet M be not excited when the lay advances in beating up the toe 9^a will move 5 in under the rack 10, and the carrier 6 will not be operated; but if the magnet be excited the toe 9^a will be protruded upward and will impinge upon and take over the end of the rack 10, thus driving said rack back and 10 through its engagement with the gear or curved rack 11 rocking the carrier 6. The carrier moves forward the bobbin-box 3, which is engaged by the fingers thereon, (see Fig. 3^a,) eventually driving it down into the shuttle 15 and knocking out or displacing the bobbin-box 3 therein, which latter falls down through the open shuttle and a slot or aperture in the lay. The shifting or changing of the bobbin-boxes in the shuttle breaks the circuit, as will 20 be hereinafter explained, and the armature-spring 9^b withdraws the toe 9^a. On the return or back movement of the lay the fingers 6^a are withdrawn from the bobbin-box in the shuttle, and the carrier 6, now free, is re- 25 turned to its normal position by a suitable spring 12. It may be well to state that when the carrier rocks forward to deposit a bobbin-box in the shuttle the curved movable section 7 of the casing moves under the bottom 30 of the magazine 2 and prevents the descent of the bobbin-boxes therein; but as the carrier moves back to the position seen in Fig. 3 the magazine is again uncovered and the lower bobbin-box therein descends and 35 engages the upright fingers 6^a. One corner or angle 3^d of the bobbin-box is rounded or cut away, so as to permit it to enter the shuttle readily, and the shuttle is open at its bottom to allow the bobbin-box to drop down 40 through when displaced.

Referring to Fig. 6, which shows the shuttle-box on the lay in side elevation, w represents an electric circuit, and G a generator supplying same. This circuit may be arranged in any way known to electricians. 45 On the shuttle-box are two spring-terminals t and t^x of said electric circuit w, and these terminals are adapted to bear, respectively, on contact-plates 13 and 13^x, set in the side of 50 the shuttle S, as best seen in Figs. 6 and 9. In the shuttle at its respective ends are mounted elastically-yielding holders for the bobbin-box 2. These hold the box in place by an elastic end pressure thereon, but yield 55 and permit it to be knocked out by an incoming box, as already explained. At the right in Fig. 8 the wooden shuttle is broken away to show the wedge-shaped yielding metal holder 14^x, which is electrically connected by a suitable wire or the like with the contact-plate 13^x, and in Fig. 9 particularly the plate 13 is shown to be electrically connected in a similar manner with the yielding cone-shaped metal holder 14 at this end of the 60 shuttle.

Figs. 9 and 10 show the bobbin 15 in detail.

It may be of wood, as usual, and has at its larger end a flanged metal ring or collar 16, which is in contact with the metal bobbin-box 3. The box 3 is open at this end and the bobbin is inserted at said opening. The ring 16 is connected electrically by a conductor 17 with a metal collar 18 on the smaller part of the bobbin. Thus it will be seen the collar 18 is connected electrically with the spring-terminal t^x when the shuttle is in its proper place in the box B, the connection being through the conductor 17, the ring 16, the metal of the box 3, and the metal holder 14^x. Within the end of the bobbin, Figs. 9 and 10, is set and insulated a metal piece, block, or ring 19, coned to receive the holder 14, and to this ring or piece is electrically connected a metallic spring contact-piece 20, which occupies a slot formed in the bobbin, and its free end takes under or within the collar 18. This contact-spring tends normally to spring outward at its free end into contact with the inner face of the collar, and as this would connect the collar 18 electrically with the circuit-terminal 13 through the said spring 20, the ring 19, the holder 14, and the plate 13 obviously the circuit would be closed; but when the filling or weft is wound on the bobbin it bears on an exposed portion of the spring 20 and presses the free end of the latter inward out of contact with the collar 18, thus holding the circuit open so long as there is sufficient filling on the bobbin to overcome the elasticity of the spring 20. When, however, the filling is nearly exhausted from the bobbin, the spring 20 will overcome the slight pressure on it and move into contact with the collar 18, thus closing the circuit at that point. This may happen when the shuttle is not in 105 the shuttle-box B; but the instant the shuttle thereafter enters this box the spring contact-terminals t and t^x on the box will be put into contact with respective plates 13 and 13^x on the shuttle, and this will complete the circuit through the electromagnet M. The effect of the excitation of this magnet in effecting the operation of the carrier 6 has been described. As the circuit in the full bobbin is broken it will be obvious that when a fresh 115 bobbin-box from the magazine enters the shuttle the operating-circuit will be broken. Thus the attendant will only be required to keep the magazine 2 supplied within the bobbins in their boxes, and the shuttle will be 120 supplied with full bobbins automatically as needed. Moreover, as the circuit will be completed before the bobbin is absolutely denuded of weft there will be no weft-shot missing in the fabric and no fault.

Fig. 7 shows how the thread from the bobbin is led out through the side of the bobbin-box. As here indicated, the weft thread or yarn y passes about a guide-pin 22 in the box and then out laterally through an aperture 13^c 23 in the side of the box, which aperture registers with a notch 24 in the side of the shuttle.

In Fig. 9, *y* represents thread on the bobbin, wound over the contact-spring 20 and holding it out of contact with the collar 18. While in the magazine the weft-thread from each bobbin-box is led to a point *z* and attached thereto.

Fig. 11 is a view showing another arrangement of the contact-spring in the bobbin. In this case the contact-spring 20^x makes contact directly with the bobbin-box 3 when the bobbin is denuded of filling. Obviously many ways of effecting this object—namely, the closing of the circuit at the bobbin when the latter is nearly or wholly denuded—would occur to any one skilled in the art, and this invention is not limited strictly in that respect. For example, Fig. 12 shows a spring-contact 20^x on the box 3 and adapted to make contact with the collar 18 when the bobbin is denuded of weft at this point. The free end of the spring 20^x bears on the weft on the bobbin.

By the word "bobbin" as herein used is meant any device for carrying the weft-thread or filling for a shuttle, such as cops, butt-cops, and the like.

Our invention, it will be noted, relates to an electrically-controlled mechanism for supplying weft to a loom while the latter is running, the object being to avoid the necessity of stopping the loom to supply it with weft as the latter is used up in the weaving. We are fully aware that an electrically-controlled weft-stop mechanism has been heretofore devised; but we are the first, so far as we are aware, in this field where the supply of weft is kept up automatically while the loom is running at full speed, the supply being controlled electrically.

In the drawings the carrier 6 is represented as moving through about a quadrant; but the invention is not limited to this extent of movement of the carrier. Obviously it might move through more or less than a quadrant. This extent of angular movement was chosen merely because it conveniently permits of the magazine being set in a vertical plane.

Having thus described our invention, we claim—

1. A mechanism for automatically supplying weft to a loom while the latter is running, comprising mechanism for supplying filled bobbins to the shuttle as required, and means for controlling the operation of said supplying mechanism, said means consisting of an open electric circuit including a generator and an electromagnet, said circuit having in it a break the terminals at the break being situated wholly within the weft on the bobbin, and the closure of said break being controlled by said weft.

2. A mechanism for automatically supplying weft to a loom while the latter is running, comprising a magazine, bobbin-boxes therein, each containing a full bobbin, a carrier for delivering the bobbin-boxes, one by one, from

the magazine to the shuttle, mechanism for operating said carrier at proper times while the loom is in motion, and means for controlling the times of operation of said carrier, 70 said means comprising an open electric circuit including a generator and an electromagnet, the said circuit having in it a break the closure of which is controlled by the weft in the shuttle.

3. In a loom, mechanism for automatically supplying weft thereto while the loom is running, said mechanism comprising a magazine, bobbin-boxes therein each containing a full bobbin, the said bobbins, each having circuit-closing appliances whereby a controlling circuit is permitted to close automatically through the removal of weft-thread from the bobbin, a shuttle, open at the top and bottom, and having yielding holders for the bobbin-box, a carrier which takes the bobbin from the magazine and deposits it in the shuttle, mechanism for operating said carrier at proper times, an open electric circuit including a generator and an electromagnet, said circuit 90 connecting with that in the bobbin when the shuttle is in its box, and controlling the operation of said carrier, whereby when the weft on the bobbin in play is nearly exhausted the circuit will be closed and a fresh bobbin supplied.

4. In a mechanism for supplying weft to a loom automatically while the latter is running, the combination with a shuttle open through from bottom to top and having yielding holders for a bobbin-box, of the said box containing a weft-carrier and having in it a partial electric circuit including two terminals situated within the mass of weft, said terminals tending to close together automatically and held apart by the weft, whereby the circuit is automatically closed when the amount of weft is sufficiently reduced.

5. In a weft-supply mechanism for looms, the combination with a stationary, upright magazine, the bobbin-boxes superposed in said magazine and provided with mortises to receive fingers on the carrier, and a rocking carrier, adapted to take the bottom box from the magazine on its fingers and deliver it in a 115 downward direction into the shuttle, substantially as set forth.

6. In a mechanism for supplying weft automatically to a loom while the latter is running, the combination with a shuttle open 120 through from bottom to top, said shuttle having external contact-plates 13 and 13^x, and spring-holders 14 and 14^x, electrically connected with the said external plates, respectively, a bobbin-box 3, of thin metal, supported in said holders, and a bobbin within said box and having within it an electric circuit of which the plates 13 and 13^x are terminals, said bobbin-circuit having in it a break closure of which is controlled by the 130 weft on the bobbin, of a magazine containing full bobbin-boxes, a vibrating carrier for

transferring the boxes from the magazine to the shuttle, mechanism for operating said carrier at proper times, and electrical means controlling the operation of said carrier and controlled by the circuit-closer in the bobbin.

7. In a loom, the combination with the lay, the shuttle-box thereon, and the shuttle, of the upright magazine, the bobbin-boxes superposed therein, the rocking carrier 6, provided with fingers 6^a to engage the lower bobbin-box, a curved rack 11, a closing-plate 7, and a retracting-spring, the sliding rack 10, gearing with the rack 11, the magnet M on the lay, its armature-lever 9 provided with an armature m, a retracting-spring, and a toe 9^a on said lever, adapted to be moved into position to actuate the rack 10 when the magnet is excited, and an electric circuit including a generator and said magnet and adapted to be completed by the denudation of the bobbin in the shuttle, substantially as set forth.

8. In a loom, the combination with the lay, the shuttle-box thereon, a bobbin-magazine, and a carrier, operated by the lay, to deliver bobbins from the magazine to the shuttle, of an electric circuit and mechanism for controlling the operations of the bobbin-carrier, said circuit having terminals t, t^x, on the shuttle-box, in electrical connection with yielding holders in the shuttle, the said holders 14 and 14^x, the bobbin-box 2, and the bobbin, having metallic parts in electrical connection, respectively, with the circuit-terminals, said metallic parts being held forcibly out of contact by thread wound on the bobbin, substantially as set forth.

9. The combination with a bobbin-box, having a bearing at one end to receive the holder in the shuttle, and an opening at the other end to receive and fit the bobbin, of the said bobbin having at its larger end a bearing to receive the holder at the other end of the shuttle, substantially as set forth.

10. The combination with the shuttle, having contact-plates and yielding holders in electrical connection, respectively therewith, of a metallic bobbin-box, and a bobbin 15, fitting therein, said bobbin having a metallic piece 16, in contact with the box, a collar 18, electrically connected with the part 16, a metallic piece 19, in contact with one of the yielding holders in the shuttle, and a contact-spring 20, electrically connected with the piece 19, and adapted to bear on the collar 18, some part of said spring 20 being exposed to be overwrapped by the thread wound on the bobbin and pressed inward out of contact with said collar, substantially as and for the purposes set forth.

11. The combination with a shuttle having an opening down through it for the passage of a bobbin-box, and yielding holders for said box, the bobbin-box having a bearing at one end to receive the holder on the shuttle and open at its other end to receive the bobbin, and having one of its angles removed to en-

able it to enter the shuttle readily, substantially as set forth.

12. As a new article of manufacture, the bobbin-box which holds the bobbin and which is adapted to fit into the shuttle, said box being open at one end to receive the bobbin and having an aperture in its side for the passage of the weft-thread, substantially as set forth.

13. A weft-holder for a shuttle containing two metallic parts of an electric circuit, both of said parts situated inside the weft on the holder and adapted to come together automatically to close said circuit, one of said parts being spring-like and in position to be overwrapped by the weft-thread on the holder and thus held out of contact with the other part until the pressure from the overwrapped thread is removed, substantially as set forth.

14. A weft-holder for a shuttle having in it a hollow containing two metallic parts of an electric circuit adapted to come together automatically to close said circuit, one of said parts being spring-like and in position to be overwrapped by the weft-thread on the holder and thus held out of contact with the other part until the pressure from the overwrapped thread is removed, whereby the said contact devices are situated wholly within the weft-holder or bobbin, substantially as set forth.

15. As a new article of manufacture, a weft-holder, adapted to go into a shuttle, provided with a part of a metallic electric circuit, said partial circuit having two terminals both situated inside of the weft-thread on said holder, and having in it a self-closing break held open by the weft-thread wound about the weft-holder, substantially as set forth.

16. As a new article of manufacture, a holder for weft to go into a shuttle, said holder having an automatic closer for an operative electric circuit containing two terminals both situated inside of the mass of weft-thread wound on said holder, said circuit-closer being held open, normally, by the weft wound on said holder, whereby the circuit is automatically closed when the pressure of the weft is removed to a sufficient extent from said closer.

17. As a new article of manufacture, a shuttle having electric-circuit terminals on its exterior surface, and containing a weft-holder bearing a partial electric circuit connecting with said terminals, said holder having an automatic circuit-closer in said circuit, and said closer containing two terminals both situated inside of the mass of weft-thread wound on the holder, said circuit-closer being held open, normally, by the weft on the holder, and adapted to close when the pressure of the weft thereon is sufficiently reduced.

18. As a new article of manufacture, a shuttle containing two partial electric circuits, one in the shuttle proper, which has terminals at the exterior face of the shuttle, and the other within the weft-holder in the

shuttle, this latter closing with that in the shuttle and having in it an automatic circuit-closer comprising two terminals, both inside the weft-thread on said holder and held open by said weft-thread, and adapted to close when the pressure of the weft-thread thereon is sufficiently reduced.

5 In witness whereof we have hereunto signed

our names this 24th day of February, 1899, in the presence of two subscribing witnesses. ^{to}
